INVENTOR

WILLIAM LLOYD

BY *Hausman and Hausman*
ATTORNEYS

UNITED STATES PATENT OFFICE.

WILLIAM LLOYD, OF HAZLETON, PENNSYLVANIA, ASSIGNOR TO COXE TRAVELING GRATE COMPANY, OF PORT CARBON, PENNSYLVANIA, A CORPORATION OF PENNSYLVANIA.

FURNACE.

1,394,421.

Specification of Letters Patent. Patented Oct. 18, 1921.

Application filed May 15, 1918. Serial No. 234,673.

To all whom it may concern:

Be it known that I, WILLIAM LLOYD, a citizen of the United States of America, residing at Hazleton, in the county of Luzerne 5 and State of Pennsylvania, have invented certain new and useful Improvements in Furnaces, of which the following is a specification.

My invention relates to furnaces and particularly to a feed hopper for furnaces of the traveling grate type, the object of my invention being to improve the hopper construction in certain particulars hereinafter described or shown in the accompanying 15 drawings, in which—

Figure 1 is a side elevation of a furnace hopper in which my invention is embodied in one form;

Fig. 2 is a broken elevation thereof;

Fig. 3 is a vertical section through the feed plate portion of the hopper;

Fig. 4 is a partial view similar to Fig. 3 but showing the ignition plate in a different position;

Fig. 5 is a partial view of the opposite end of the hopper from that illustrated in Fig. 2;

Figs. 6 and 7 are sections on the lines 6—6, 7—7, respectively, in Fig. 3;

Fig. 8 is a vertical section on the line 8—8, Fig. 10, through a hopper showing a modified construction of certain details;

Fig. 9 is a section on the line 9—9, Fig. 8;

Fig. 10 is a broken elevation of the hopper shown in Fig. 8;

Fig. 11 is a broken plan of the same, and

Fig. 12 is a perspective of the adjusting mechanism.

In its general features the present hopper 40 resembles that shown in my copending application Serial No. 219,255 and comprises a pair of side uprights 20—21, between which extends the fixed outer wall 22 secured to transverse angle irons 23—24, 45 which, with the uprights, form the frame of the hopper. A cut-off gate 25 is pivoted at 26 in the upper portion of the hopper and is operated by a lever 27 through toggle links 28 and 29 pivoted on the cross shaft 50. The construction of this cut-off gate is 50 similar to that shown in my application above mentioned, as is also the construction of the regulating gate 31, which need not be described in detail.

The features of improvement indicated in 55 Figs. 1 to 7 inclusive relate primarily to the ignition plate 32 and particularly to the means for adjusting the latter with relation to the regulating gate 31. As here shown the ignition plate is provided at opposite 60 sides of the lower portion thereof with trunnion pins 33 secured thereto by bolts 34. The bearings for these trunnion pins consist of recesses or boxes 35 let into the lower portions of the side uprights 20 and 21 and 65 inclined downward toward the fire chamber 36, Fig. 1. These boxes are elongated and afford bearings in which the trunnions may slide. The upper margin of the ignition plate underlies the lower edge of the hopper 70 plate 22 and is supported in this position by the blocks 37 and 38, against which it freely rests. The margins of these blocks are slotted at 39 to receive the securing bolts 40, which thus afford a quickly detachable connection for the blocks and enable the attendant to remove them when the plate 32 is to be dropped for slicing the fire. The bearing faces 41 of the supporting blocks 75 are preferably curved as shown.

To shift the ignition plate in its slot bearings 35, a pair of bars 42 is provided, one at each end of the ignition plate, engaging the trunnions 33. The outer ends of the bars are provided on their lower faces with 80 racks 43 which mesh with pinions 44 on the cross shaft 45 journaled in bearings 46 bolted to the side uprights. The guides 47, through which the outer ends of the bars 42 pass, are provided with hubs 48 centered on the 85 bearings 46, so that they are concentric with the shaft 45 and insure the proper meshing of the racks 43 of the bars 42 with the pinions 44 on the cross shaft 45, irrespective of the various angular positions assumed by the bars on the regulation of the position of the ignition plate. On one end of the cross shaft 45 I mount an operating handle 49 which carries a locking clamp 50, the stem of which passes through the slot 100 51 of the clamp plate 52, which may be formed as a flange at the end of the adjacent bearing 46 for the cross shaft 45. Obviously, upon the rotation of this shaft 45, through the operation of the handle 49, the 105 trunnion pins 33 of the ignition plate 32 are shifted longitudinally of the bearing boxes 35, thus varying the inclination of the igni-

tion plate with relation to the regulating gate 31. This has the effect of increasing or decreasing the thickness of the fuel bed which flows from the ignition plate to the traveling grate 53. Moreover, it has the further advantage of regulating the inclination of the fuel bed as it enters the fire chamber. Furthermore, the prompt ignition of the fuel at the hopper end of the 10 furnace is largely dependent upon the proper positioning of the ignition plate with relation to the furnace arch at this point, and the proper position varies not only with the character of fuel used, but with the draft 15 employed. The means which I have provided permits a very nice regulation of the position of the ignition plate to suit varying conditions of operation. It will be noted that the range afforded extends from 20 a position within the fire box to a position well behind the arch at the ignition or hopper end of the fire box.

Obviously, the position of the trunnions in the slots 35 does not affect in any way the 25 lowering of the ignition plate to permit slicing of the fire bed by the attendant when that becomes necessary. To drop the ignition plate, the supporting blocks 37, 38 are removed by loosening the bolts 40, whereupon the plate drops by gravity to the position indicated in Fig. 4. The handles 320 secured to the top of the ignition plate permit the operator to lift and lower the plate without difficulty. The inclination of the 30 bearing slots 35 serves to maintain the nose of the ignition plate at substantially the same distance from the grate 53 irrespective of the position imparted to the ignition plate through the adjusting shaft 45. In other words the inclination of the slots 35 is so predetermined with respect to the distance 35 from the trunnions 33 to the nose of the ignition plate 32 that the spacing of the nose from the face of the grate bars 53 is maintained substantially constant regardless of the different inclinations of the ignition plate 40 incident to the longitudinal adjustment of the trunnions in the slots 35.

In the modification illustrated in Figs. 50 8, 9, and 10, the ignition plate consists of a series of flat blocks 54 without the usual protective fire brick or casting shown in Figs. 1 to 7. The trunnions 55-56 are bolted to an angle iron 57 and work as previously described in the elongated bearing boxes 35 in the side uprights. Instead of adjusting gear of the type shown in Figs. 1 to 7, I have provided the bars 58, which engage the trunnions, with threaded outer ends 59, on 55 which screw the thumb nuts 60 held against longitudinal movement on the screws by ring bearings 61 strapped at 62 to the side uprights. A second angle iron 63 stretches across the upper portion of the ignition

plate, and the end blocks 54 are bolted there- 65 to at 64 as well as to the lower angle iron 57. The intermediate blocks 54 are loosely supported in position by hook flanges 65-66 which project from ribs on the backs thereof, while their side margins are offset at 67 70 to form lap joints with adjacent sections. Obviously, these central blocks 54 may be readily replaced by simply lifting them out and dropping new ones into engagement with the angle irons 57 and 63. The handles 75 540 are carried by the end blocks.

In Figs. 8 and 11 I have indicated the cut-off gate 68 also made in sectional form, the several segments 69 thereof being bolted at 70 to transverse angle irons 71 and 72 which 80 form a supporting frame. This construction has the advantage of being readily and economically formed from metal plates and standard rolled angles.

In order to secure precise alinement of 85 the lower edge of the regulating gate 31 with the upper surface of the grate 53, and thus insure a fuel bed of equal depth across the entire width of the grate, I provide means for vertically adjusting one end of 90 the gate with relation to the other. For this purpose I provide at one end of the lifting shaft 73 a pinion 74 keyed thereon, while the pinion 75 at the other end of the shaft is free. Adjacent the latter is a hub 76 keyed 95 to the shaft. Abutting flanges 77 and 78 are provided on the pinion and hub respectively, one of these flanges carrying bolts 79 and the other having arcuate slots 80 formed therein to receive the shanks of the bolts. 100 The slots 80 are of such arcuate extent as to permit the rotation of the pinion 75 with relation to the shaft 73 a sufficient distance to take up inaccuracies in alinement of the regulating gate, which may be due to error 105 in castings, key ways, or screw hole layouts. The tightening of the bolts 79 of course secures the hub 76 and pinion 75 rigidly together, so that the pinions actuate the usual 110 lifting bars 81 and 82 in unison. An adjusting mechanism of this character is particularly applicable to stokers of relatively narrow width. For stokers of a width exceeding six feet it is preferred to use an independent lifting device at each side of the 115 regulating gate, such, for example, as that illustrated in my copending application 219,255.

Various modifications in detail of construction will readily occur to those skilled 120 in the art which do not depart from what I claim as my invention.

I claim:

1. In a mechanical stoker, a hopper, an ignition plate over which the fuel passes from the hopper to the furnace grate, and means for adjusting said ignition plate bodily toward and from the fire box, together 125

with a cut-off gate arranged in the hopper above the ignition plate and serving to control the supply of fuel to the ignition plate.

2. In a mechanical stoker, a hopper, an ignition plate over which the fuel passes from the hopper to the furnace grate and means for adjusting the lower end of the ignition plate from a point within the hopper to a point within the fire box of the furnace.

10 3. In a mechanical stoker, a hopper, an ignition plate over which the fuel passes from the hopper to the furnace grate, a pivotal support for the lower portion of the ignition plate, and means for adjusting said 15 pivotal support toward and from the fire box.

4. In a mechanical stoker, a hopper, an ignition plate over which the fuel passes from the hopper to the furnace grate, a pivotal support for the lower portion of the ignition 20 plate, and slide bearings in which said pivotal support may be advanced toward or retracted from the fire box.

5. In a mechanical stoker, a hopper having side uprights recessed at their lower portions to form slide bearings, an ignition plate over which the fuel passes from the hopper to the furnace grate, trunnions for the lower portion of said ignition plate, said 30 trunnions resting in said slide bearings in the side uprights of the hopper, and means for shifting said trunnions in said slide bearings.

6. In a mechanical stoker, a hopper having side uprights recessed at their lower portions to form slide bearings inclined downward from their outer toward their fire box ends, an ignition plate over which the fuel passes to the furnace grate, trunnions for 40 the lower portion of said ignition plate, said trunnions resting in said inclined slide bearings in the side uprights of the hopper, and means for shifting said trunnions in said slide bearings.

45 7. In a mechanical stoker, a hopper, an ignition plate having trunnions at its lower side margins upon which said ignition plate is pivotally supported, slide bearings for said trunnions and adjusting bars engaging 50 said trunnions, and means for advancing and retracting said adjusting bars to shift said trunnions in their bearings.

8. In a mechanical stoker, a hopper, an ignition plate over which the fuel passes 55 from the hopper to the furnace grate, said ignition plate comprising a series of inde-

pendent sections and supporting means on which at least some of said sections are freely mounted.

60

9. In a mechanical stoker, a hopper, an ignition plate over which the fuel passes from the hopper to the furnace grate, said ignition plate comprising a pair of transverse angle irons and a series of independent 65 sections carried by said angle irons.

10. In a mechanical stoker, a hopper, an ignition plate over which the fuel passes from the hopper to the furnace grate, said ignition plate comprising a pair of transverse angle irons and a series of independent 70 sections carried by said angle irons, certain of said sections being freely engaged with said angle irons.

11. In a mechanical stoker, a regulating 75 gate, lifting rack bars attached thereto, a lifting shaft, pinions thereon meshing with said rack bars, one of said pinions being keyed to the shaft and the other free thereon, together with a hub keyed to said shaft 80 adjacent the free pinion and means for securing said hub to the free pinion in different relative rotary relations of said hub and pinion.

12. In a mechanical stoker, a hopper, a 85 fuel-bed-regulating element associated with said hopper, rack bars secured to said regulating element, a shaft and pinions thereon engaging said rack bars, one of said pinions being fast on said shaft and the other free 90 thereon, together with a hub keyed to said shaft adjacent said free pinion, and means for securing said hub and free pinion together in various relative rotary positions of the parts, for the purpose described.

95 13. In a mechanical stoker, a hopper, an ignition plate over which the fuel passes to the furnace grate, means for supporting said ignition plate, and means for shifting said support toward and from the fire box, for 100 the purpose described.

14. In a mechanical stoker, a hopper, an ignition plate over which the fuel passes to the furnace grate, means engaging the lower portion of said plate to support the same, and means for shifting said support toward and from the fire box to vary the position and inclination of the ignition plate with reference thereto.

In testimony whereof I have signed my name to this specification.

WILLIAM LLOYD.
